UNITED STATES PATENT OFFICE.

LEWIS P. HALLADAY, OF DECATUR, ILLINOIS.

AUTOMOBILE BUMPER.

Application filed February 21, 1924. Serial No. 394,236.

To all whom it may concern:

Be it known that I, LEWIS P. HALLADAY, a citizen of the United States, residing at Decatur, in the county of Macon and State of Illinois, have invented a certain new and useful Improvement in Automobile Bumpers, of which the following is a specification.

My invention relates to improvements in automobile bumpers and particularly to the clamp assembly whereby the separate bumper bar elements are held in rigid assembled non-adjustable, though demountable relation. It has for one object to provide a new and improved form of clamp assembly by which the bars may be rigidly, though demountably fastened together and by which the same clamp assembly may be used to assist in attaching the impact bar to an automobile frame or other suitable supporting element. Other objects will appear from time to time in the specification and claims.

My invention is illustrated more or less diagrammatically in the accompanying drawings, wherein—

Figure 1 is a front elevation;

Figure 2 is a plan view;

Figure 3 is a section along the line 3—3 of Figure 1;

Figure 4 is a section along the line 4—4 of Figure 3;

Figures 5, 6 and 7 are detail views of modified forms.

Like parts are indicated by like characters throughout the specification and drawings.

A, A¹ are parallel upper and lower flat strip impact bars. They may be made of spring steel and may be finished at their ends in any suitable manner. They extend normally clear across the front of the motor vehicle. The upper and lower opposed edges of the bars A, A¹ are notched in opposition at A² and A³. These notches are cut in the metal and formed before the assembly takes place.

B, B are front clamp members overlying the front impact faces of the bars and having rearwardly and upwardly and downwardly bent ends B¹, B², these hooks engaging the upper and lower edges respectively of the impact bars. B³ is a bolt having a round head to engage the front face

of the clamp member B, a squared shank 55 B⁴ located in a centrally disposed aperture in the clamp B and extending backwardly between the impact bars A, A¹. B⁵ is a rear clamp member having a spacing block B⁶ lying between the opposed edges of the impact bars and provided with lugs B⁷ and B⁸ engaging the notches A², A³ and overlying lugs B⁹ projecting beyond the notch engaging lugs and engaging the rear sides of the bars A, A¹. B¹⁰ is a pocket in the 60 clamp B⁵ adapted to contain a nut B¹¹ which when screwed home on the bolt B³ clamps the two impact bars together between the two clamp members and is entirely contained within the recess so as to leave a 70 flared uninterrupted surface at the back of the rear clamp. B¹², B¹³ are ribs on the back of the clamp projecting rearwardly to form a channel adapted to engage and position a holding or reinforcing bar B¹³. 75 In the preferred form, this bar B¹³ extends across the back of the bumper and has forwardly and inwardly curved ends B¹⁴ engaging the channel formed between the ribs on the back clamp. The ends of this bar 80 are perforated as at B¹⁵ to engage the bolt B³ and the nut B¹⁰ is provided to lock the parts together.

It will be noted that the fact that the ends of the reinforcing bar are apertured 85 to engage the bolt and the further fact that the impact bars are notched to engage lugs in the clamps prevents any displacement or movement of the bumper parts after they are once assembled and particularly prevents any relative movement of the two impact members with respect to one another or with respect to the reinforcing or holding bar.

In the modified form shown in Figure 5, 90 the back clamp member has no recess and the nut B¹¹ engages the back of the clamp. An integral lug C projects rearwardly from the clamp and may be bolted or riveted to the forward end C¹ of the cross bar C². 100 In Figure 6, the lug C² is substituted. This extends clear back so that the rear bar C¹ is straight without the forward bent extension and may be bolted or riveted to the lug C³.

In the further modified form shown in Figure 7, the back bar B¹³, C² or C³ is dispensed with and the bracket C⁴, upon

which the clamp B⁵ is mounted, projects forward direct from the automobile frame.

It will be evident that while I have shown in my drawings, an operative device, still 5 many changes might be made in the size, shape and disposition of parts without departing materially from the spirit of my invention. I wish, therefore, that my showing be taken in a large sense as diagrammatic.

I claim:

1. In an automobile bumper, a plurality of impact bars arranged edge to edge, a front clamp engaging their impact faces 15 and having hooked ends to engage their separated edges, a spacing clamp located between the bars and provided with lugs engaging notches in their opposed edges and arms engaging their rear sides and means 20 for drawing the clamps together to hold the bars in fixed relation.

2. In an automobile bumper, a plurality of impact bars arranged edge to edge, a front clamp engaging their impact faces and 25 having hooked ends to engage their separated edges, a spacing clamp located between the bars and provided with lugs engaging notches in their opposed edges and arms 30 engaging their rear sides and means for drawing the clamps together to hold the bars in fixed relation comprising a bolt passing through the two clamps squared to engage a square hole in the front clamp to prevent turning and a nut adapted to be 35 completely enclosed within a recess on the back of the spacing clamp.

3. In an automobile bumper, a plurality of impact bars arranged edge to edge, a front clamp engaging their impact faces 40 and having hooked ends to engage their separated edges, a spacing clamp located between the bars and provided with lugs engaging notches in their opposed edges and arms engaging their rear sides and means 45 for drawing the clamps together to hold the bars in fixed relation, and a reinforcing bar located behind the impact surface having its end forwardly and inwardly turned to engage the spacing clamp.

50 4. In an automobile bumper, a plurality of impact bars arranged edge to edge, a front clamp engaging their impact faces and having hooked ends to engage their separated edges, a spacing clamp located 55 between the bars and provided with lugs engaging notches in their opposed edges and arms engaging their rear sides and means for drawing the clamps together to hold the bars in fixed relation comprising a bolt passing through the two clamps squared to engage a square hole in the front clamp to prevent turning and a nut adapted to be 60 completely enclosed within a recess on the back of the spacing clamp, and a reinforcing bar located behind the impact surface 65

having its end, forwardly and inwardly turned to engage the spacing clamp and means associated with the bolt for holding the reinforcing bar in position on the clamp.

5. In an automobile bumper, a plurality of impact bars arranged edge to edge, a front clamp engaging their impact faces and having hooked ends to engage their separated edges, a spacing clamp located between the bars and provided with lugs 70 engaging notches in their opposed edges and arms engaging their rear sides and means for drawing the clamps together to hold the bars in fixed relation, a pair of parallel spaced lugs projecting rearwardly from the spacing clamp to form a channel thereon.

6. In an automobile bumper, a plurality of impact bars arranged edge to edge, a front clamp engaging their impact faces and having hooked ends to engage their separated edges, a spacing clamp located 75 between the bars and provided with lugs engaging notches in their opposed edges and arms engaging their rear sides and means for drawing the clamps together to hold the bars in fixed relation, a pair of parallel spaced lugs projecting rearwardly from the spacing clamp to form a channel 80 thereon and means engaging said clamp and located within the channel for holding the bumper in position on an automobile frame.

7. In an automobile bumper, a plurality of impact bars arranged edge to edge, a front clamp engaging their impact faces and having hooked ends to engage their separated edges, a spacing clamp located 85 between the bars and provided with lugs engaging notches in their opposed edges and arms engaging their rear sides and means for drawing the clamps together to hold the bars in fixed relation, a pair of parallel spaced lugs projecting rearwardly from the spacing clamp to form a channel 90 thereon and means engaging said clamp and located within the channel for holding the bumper in position on an automobile frame.

100 8. In an automobile bumper, a plurality of impact bars arranged edge to edge, a front clamp engaging their impact faces and having hooked ends to engage their separated edges, a spacing clamp located 105 between the bars and provided with lugs engaging notches in their opposed edges and arms engaging their rear sides and means for drawing the clamps together to hold the bars in fixed relation, a pair of parallel spaced lugs projecting rearwardly from the spacing clamp to form a channel 110 thereon and means engaging said clamp and located within the channel for holding the bumper in position on an automobile frame, said frame comprising in part a reinforcing bar located behind the impact faces of the bumper and having an end extension located 115 within said channel.

120 8. In an automobile bumper, a plurality of impact bars arranged edge to edge, a front clamp engaging their impact faces and having hooked ends to engage their separated edges, a spacing clamp located between the bars and provided with lugs engaging notches in their opposed edges and arms engaging their rear sides and means for drawing the clamps together to hold the bars in fixed relation comprising a bolt passing through the two clamps squared to engage a square hole in the front clamp to prevent turning and a nut adapted to be 125 completely enclosed within a recess on the back of the spacing clamp, and a support 130

ing strip engaging said back clamp and said bolt and a separate nut adapted to hold the back clamp and supporting strip together on the bolt.

5. 9. In an automobile bumper, a plurality of impact bars spaced and arranged edge to edge, clamping means for demountably holding said bars in position, said means adapted when assembled to hold the parts 10 together against relative movement, said means comprising clamping elements located on both sides of the bars and having lugs engaging notches in the bars so disposed that when the clamping elements are 15 held together, relative movement of bars and clamping elements is prevented.

10. In an automobile bumper, a plurality of impact bars, one superposed above another, arranged edge to edge, the opposed 20 edges of the bars being notched, clamping means for demountably holding said bars in

position, including in part a clamping element penetrating between the bars and having lugs on its top and bottom sides engaging the notches in the bars. 25

11. In an automobile bumper, a plurality of impact bars, one superposed above another, arranged edge to edge, the opposed edges of the bars being notched, clamping means for demountably holding said bars in position, including in part a clamping element penetrating between the bars and 30 having lugs on its top and bottom sides engaging the notches in the bars, and a reinforcing bar positioned behind the impact bars, said clamping element being channeled 35 to receive said reinforcing bar. 40

Signed at Chicago, county of Cook and State of Illinois, this 15th day of February 1924.

LEWIS P. HALLADAY.
